ATTORNEY

UNITED STATES PATENT OFFICE.

FREDERICK E. KOHLER, OF CANTON, OHIO.

HAY-TEDDER.

SPECIFICATION forming part of Letters Patent No. 336,723, dated February 23, 1886.

Application filed August 13, 1885. Serial No. 174,318. (No model.)

To all whom it may concern:

Be it known that I, FREDERICK E. KOHLER, a citizen of the United States, and a resident of Canton, county of Stark, State of Ohio, have invented a new and useful Improvement 5 in Hay-Tedders, of which the following is a full, clear, and exact description, reference being had to the accompanying drawings, making part of this specification.

10 My invention relates to improvements in hay-tedders, and in providing means by which the tedder-frame may automatically adjust itself to uneven surfaces.

15 A further object of my invention relates to and consists in providing a spring or yielding connection between the tedder-frame and the thill-frame.

20 With these objects in view my invention consists in certain features of construction and combination of parts hereinafter described, and set forth in the claims.

25 Figure 1 is an isometrical view of my invention, showing the parts in normal position. Fig. 2 is a sectional view showing one form of applying my invention. Fig. 3 is a view in perspective of the spring-bar, showing the manner of adapting it to the hand-lever.

30 A A are the main supporting and driving wheels. Each of these wheels has upon its inner face a concentric cogged rim, B, which may either have independent spokes a a of its own projecting from the hub of the supporting-wheel, or it may be bolted or otherwise secured to the spokes of the main wheel 35 in any usual or approved manner.

35 C is the through-axle, preferably of wood and square in cross-section.

D D d' are bars arranged transversely on the axle.

40 E E' are bars or girts parallel to the axle, which, with the bars D d d', constitute the main frame. This main frame is pivoted to the axle eccentrically—that is, on a line other than the center of the axle, which forms the 45 axis of the cogged rims by means of ears or lugs c c, bolted to the upper surface of the axle, which by preference is flat, but may be of other shape, with a corresponding change in the under surface of the lugs.

50 F F are the thills hinged at their rear ends to transverse bars or rails D D, and con-

nected by means of bars f f', substantially as is customary in this class of tedders.

G g are bars at right angles to bars f f', and H is a lever attached to crank-shaft R, journaled upon the bars G g, and connected by links h h with the bars D D at the front of the main frame.

55 h' is a sector-plate mounted upon the bar G, and provided with a series of notches, into which a locking-latch of lever H takes, by means of which device the main frame can be tilted or vibrated about the axle C.

60 I is the crank-shaft, having a series of cranks in different relative positions. This crank-shaft is mounted upon the rearwardly-projecting ends of the transverse bars D d d', and carries at each end a pinion, i, which engages with the cogged rims B. The shipping-lever J is bolted rigidly to the front face of 70 the main axle C; and b is a sector-plate bolted to the side of the longitudinal beam d, and provided with notches to receive the locking-latch carried by the lever J.

75 K K are arms, each mounted upon a crank about midway between its ends, and connected at its upper end to the bar E' by means of a link, l, substantially as is customary in this class of tedders.

80 M are the tedder-teeth, each formed of a single piece of wire, three, four, or more convolutions at m, and an inwardly-turned spur or locking-arm, N, at its upper end. This spur is seated in a socket formed for its reception in the tooth-arm K, the tooth being 85 further secured to the arm by means of a clip, k, which is bolted to the arm K. Lever H is provided with a curved iron rod, Q, projecting rearwardly and downwardly in the arc of a circle passing through a perforation 90 in the upper end of bracket P, which is mounted upon the frame-piece G in the rear of the lever H. Above this rod Q and below the bracket P there is a coil-spring, W, resting on a cross-pin or any other suitable device, for preventing the rod from drawing out of the spring. This rod may be from fifteen to twenty inches in length and of 95 about five-eighths of an inch in diameter, the spring of about No. 10 wire and coiled 100 on a pitch of about four to the inch and to be about the full length of the rod P.

The upper end of the rod Q is bifurcated and provided with a spring-bolt, S, by which it is attached to the lever H. The bolt S is provided with a coil-spring, r, within the frame s, 5 one end of this spring resting against the frame, the other against a pin passed through the bolt, serves to hold the bolt in position, as shown in Fig. 3. By taking hold of the handle of the rod P from the lever H. Lever H is provided with a bell-crank-handle lever, T, to operate the catch-bolt T in the usual way, and also is provided with a ring, u, that may be passed over the end of the lever T, so as to hold 10 the catch-bolt out of engagement with the sector h' and allow the lever H to vibrate freely about the sector, influenced only by the oscillations of the main frame through the links h and shaft R, the weight of which, when thus 15 connected, rests on the spring w. By this arrangement of parts the main frame will be free to oscillate about the main axle during the progressive movement of the tedder, so that in case the tedder-forks M come in contact with 20 ridges or mounds of ground or other obstruction the frame will yield to the pressure, the rear part rising, the front part dropping, and in its downward movement is resisted only by the spring w, through and by means of the rod 25 Q, lever H, rod R, and link h, which, after passing such obstructions, will restore the parts to their former position and avoid breakage or damage, which is usual in tedders not so constructed; and, further, this yielding connection 30 between the main frame and the thills will allow of the setting of the tedder-forks much closer to the ground without the usual liability of breakage.

The operation of the spring M may be assisted 35 or resisted by the hand of the operator on the lever H; or, the ring-keeper u may be thrown off at any moment, releasing the handle-lever T, and the catch-bolt and the frame be held in a rigid or fixed connection with the thills, and the 40 spring-bolt S drawn back, releasing the spring-rod Q from engagement with the lever H.

By use of the lever J the pinion i may be

thrown into or out of engagement with the cogged rims B, to either start or stop the movement of the crank-shaft and tedders. 50

Having thus fully described the nature and operation of my invention, what I desire to secure by Letters Patent is—

1. The combination, in the hay-tedder, of the oscillating tedder-forks, the main vibrating frame, hinged thills, links h, shaft R, lever H, rod Q, bracket P, and spring w, substantially as described, and for the purpose set forth. 55

2. In a hay-tedder, the combination, with an axle, a main frame pivoted thereto, thills pivotally secured to the main frame, a lever journaled to the thills, and devices, substantially as described, connecting the lever and main frame, of the bracket secured to the thills, a curved rod secured to the lever and passing 60 through the bracket, and a spring encircling the rod and bearing against the bracket, all of the above parts operating substantially as set forth. 65

3. The combination, with the main frame, thills pivotally secured thereto, a lever journaled to the thills, and devices, substantially as described, connecting the lever and main frame, of the curved rod, the spring-bolt for securing the rod to the lever, the bracket secured to the thills, and a spring secured on the rod and bearing 70 against the bracket, substantially as set forth. 75

4. The combination, with an axle, the main frame pivoted eccentrically thereon and thills pivotally secured to the main frame, of a lever secured to the axle, a sector secured to the main frame, and devices for locking the axle to the sector, the bracket secured to the thills, the rod secured to the lever and passing through the bracket, and the spring encircling the rod and 80 bearing against the bracket, substantially as set forth. 85

In testimony whereof I have hereunto set my hand.

FREDERICK E. KOHLER.
